UNITED STATES PATENT OFFICE.

JOHN F. FARRINGTON, OF FLUSHING, NEW YORK, ASSIGNOR TO WESTERN ELECTRIC COMPANY, INCORPORATED, OF NEW YORK, N. Y., A CORPORATION OF NEW YORK.

TWO-WAY SIGNALING SYSTEM.

Application filed January 9, 1924. Serial No. 685,160.

The present invention relates to two-way signaling systems and more particularly to two-way signaling systems employing high frequency current.

5 This application is a continuation in part of Farrington application, Serial No. 432,644 filed December 23, 1920, which eventuated into Patent 1,566,469, granted December 22, 1925.

10 A two-way high frequency system, for the purposes of the present specification, is a system employing signal modulated carrier currents in which transmission and reception may occur simultaneously without too great 15 interference and too great side tone. Conversation can accordingly be carried on over such a two-way system in the same manner as in ordinary wire telephone systems employing only voice frequencies.

20 In signaling systems employing modulated waves it is common to provide a modulator by which the high frequency or carrier waves or currents are controlled in accordance with the signals to be transmitted and 25 a detector or demodulator for deriving from the received signal modulated wave, the current component representing the signal to be received. In such systems, balanced circuits are usually provided for making the 30 detector neutral with respect to the modulator so that the high frequency modulated energy from the output circuit of the modulator does not enter the local detector circuit. In U. S. patent to H. W. Nichols 35 1,519,626 granted December 16, 1924, a system is disclosed in which a single high frequency set is used for both modulating and detecting and this set is connected to the line or to the antenna through a single coupling or tuned circuit or filter, thus dispensing 40 with high frequency balance.

45 In the system of Nichols's patent, detection occurs by reason of the curvilinear relation between the plate potential and space current of a three-electrode vacuum tube coupled to the antenna, this tube also being used to amplify the modulated current during transmission. It is important in such a system that the production of audible frequency interfering currents, during transmission, in the circuit containing the indicating device be kept within reasonable limits, not only for the comfort of the operator 50 but also to avoid injuring the indicating de-

vice or an amplifier in the channel which 55 leads to it. Furthermore, it is desirable in a two-way system that the person speaking be able to hear the signals from distant station above the sound produced in the indicator by these interfering currents. This enables 60 the operator at the distant station to interrupt the speaker as in an ordinary wire telephone conversation.

In such a system, audible frequency current may be produced in the indicator both 65 on account of the signal side tone resulting from detection of the impressed carrier and the signal modulated side bands, and on account of a beat current resulting from interaction between the incoming and outgoing 70 carrier waves. Side tone would theoretically be avoided if a linear relation between the grid potential and space current and a curvilinear relation between the space potential and the space current of the amplifier could be made independently to exist. An approach toward the attainment of this 75 result could be made with a tube which operated according to Van der Bijl's equation 80 $I_b = K (E_b + \mu E_g + K_t)^2$, if a tube were used 85 which had a variable μ . A means for substantially balancing out the signal side tone is disclosed in U. S. patent to Heising, Serial No. 1,464,097, granted August 7, 1923. The interfering beat note resulting from the 90 combination of the currents of two carrier frequencies can be avoided by accurately synchronizing those two frequencies, but this result is difficult of accomplishment with simple means.

90 The object, broadly, of the invention is to provide for two-way signaling characterized by continuous transmission in both directions of a carrier wave and the use of a common element for translation of outgoing 95 waves and for incoming signal detection in which the interference due to the detected beat of the two carrier waves is entirely avoided.

Additional objects of the invention are to 100 provide two-way signaling systems characterized by simplicity, low cost of construction and a minimum number of vacuum tubes.

105 These objects are realized, in one modification, in a system similar to that described but in which the two carrier frequencies for opposite directions of transmissions are

caused to differ by an inaudible amount or by an amount greater than the essential signal frequencies, the antenna being doubly tuned to efficiently transmit and receive currents of the respective frequencies.

In another modification the common element functions as an oscillator in the transmitting circuit and as a detector, although not necessarily on account of its two-electrode 10 characteristic, in the receiving circuit.

In the drawing, Figs. 1 and 2 illustrate circuit-diagrams of two alternative forms of the invention as applied to a radio telephone system.

Referring to Fig. 1, a modulation system 15 constituted by modulator M, carrier current source 1, low frequency source 2 of the modulating currents, and their interconnected circuits, is coupled to antenna 3 through the power amplifier A. The modulation system is of the type disclosed in U. S. patent to Van der Bijl, No. 1,350,752, granted August 24, 1920. Its function is to produce a wave having the frequency of the current from 25 source 1, the amplitude of which varies in accordance with the current from source 2. The present invention is not dependent upon the employment of this or any other particular system of modulation. The arrangement 30 is disclosed merely as a practicable example of a modulation system well adapted to be used with the present invention.

Current from the modulation system is impressed on amplifier A through transformer 35 4. Condenser 13 which prevents the flow of direct current from space current source 14 in the primary of transformer 4, is of such capacity as to also effectively prevent the flow of amplified voice currents therethrough 40 while interposing negligible impedance to the high frequency modulated currents. The output circuit of the amplifier is coupled through tuned circuit 9 and transformer 6 with branch 5 of the antenna. Branch 5 in 45 combination with the aerial portion of the antenna is tuned to the mean frequency of the outgoing modulated carrier wave. Loop circuit 8 in the other branch 7 is anti-resonant at this frequency so as to effectively remove this branch from the antenna circuit 50 so far as its function during transmission is concerned.

The output circuit of amplifier A is completed through condenser 10 which should 55 be of such capacity as to offer negligible impedance to currents having frequencies of the order of the outgoing carrier frequency but to offer high impedance to currents of the signal frequency.

Space current for amplifier A is supplied 60 from battery 11 through telephone receiver, or other equivalent indicator, 12. Antenna branch 7 is tuned in combination with branch 5 and the aerial portion of the antenna to the mean frequency of the incoming modulated

carrier wave, the carrier frequencies for the two directions of transmission being chosen so as to differ by an inaudible amount.

During transmission, the system functions in a manner which needs little detailed discussion. Since telephone receiver 12 interposes a high impedance to the high frequency currents such currents will accordingly complete their circuit through the condenser 10 in shunt therewith. Voice frequency currents do not appear in the output circuit of the amplifier on account of condenser 13 in the output circuit of the modulator, as explained above. The receiver 12 accordingly will in no way be affected by the operations 70 incident to signal transmission except to the extent that the amplifier additionally functions as a three-electrode detector to reproduce the signal wave in its output circuit from the impressed unmodulated and signal 75 modulated carrier. The side tone produced in this manner is, in general, not useful and is usually sufficient to make the system undesirable for two-way operation, but it can be made of small volume by the method above 80 mentioned, namely, by using a tube which amplifies without distortion, but which has a curvilinear relation of its space-potential and space current, or by the method of Fig. 2 85 to be described later. 90

During reception, the signal modulated wave which is incident on antenna 3 is selectively received thereby and impressed on the plate-filament circuit of amplifier A. On account of the curvilinear relation between the 95 space current and plate voltage of this circuit, detection will occur. The signal component resulting from detection will be indicated in telephone receiver 12. 100

In practicable two-way systems of this 105 general type, the carrier currents are continuously transmitted in both directions. Their coaction in the space current circuit accordingly results in a beat note at all times. Although in such a system using identical 110 carrier frequencies for the two directions, a zero beat would theoretically result, as a practical matter it would be necessary to go to considerable trouble to insure sufficiently accurate synchronism of the two frequencies, 115 or to compromise with a lesser degree of synchronism with the attendant intermittent and variable frequency beat note. During reception this note will be superposed on, and accordingly to some extent will obscure, the 120 received signal. During transmission or reception there will result a beat current in the receiver which, on account of the relatively great amplitude of the transmitted carrier current will be injurious to the receiving instrument, and will give rise to a note which would be painful to the ear of the operator, and which might so completely drown out any simultaneously received signal as to render it impossible for a distant operator to 125 130

break in on the transmission. During transmission this effect will, of course, be increased by the signal side tone, if present.

The detrimental effect of this beat frequency is avoided in the arrangement of this figure, without the introduction of undesirable effects, by using carrier frequencies which differ from each other by a frequency above the upper frequency essential for proper speech or other signal transmission, so that the telephone receiver diaphragm either cannot respond to the resultant beat frequency or so that current of this frequency can be separated from the current of signal frequency.

The alternative system of Fig. 2 is described in detail in applicant's Patent 1,566,469, granted December 22, 1925. For this reason, and because the essential features which are common to the systems of the two figures have been described with reference to Figure 1, it will be sufficient to point out only the special features which distinguish the system of Fig. 2 from that of Fig. 1.

In Fig. 2 the elements having functions similar to the corresponding elements in Fig. 1 are similarly labelled. The common element in the transmitting and receiving circuits is oscillator O. This oscillator is of the type described in Colpitt's United States application, Serial No. 214,971, filed February 1, 1918. The anode and control electrode of the electrode discharge device are connected to the circuit of the antenna in such a manner that the antenna itself constitutes the frequency determining circuit of the oscillator. Any other equivalent form of oscillator may be used. The particular form illustrated perhaps has special advantages in connection with the system of modulation with which it is associated, although with respect to the modulation system, as in the case of the oscillator, other equivalent systems could be used.

The modulation system is of the form commonly denominated the "constant current modulation" system. It is described, for example, in United States patent to Schelleng No. 1,437,021, granted November 28, 1922. In this system the modulator or variable impedance tube M is functionally equivalent to an amplifier for the signal currents from source 2. The variation of current in the output of modulator M, resulting from the impressed signal variations, causes a corresponding variable potential drop in low frequency choke 15 and consequently similar variations in the electromotive force impressed upon the plate of the oscillator tube, since the plate-filament circuits of the oscillator and modulator are supplied in common from direct current source 16 through the choke. These variations of plate potential are effective to cause corresponding variations or modulations of the generated car-

rier oscillations. Choke coil 17 has high impedance to the high frequency current from the oscillator and accordingly prevents them from reacting on the low frequency circuits. Its impedance is insufficient at low frequencies to interfere with the flow of signal frequency currents to the oscillator.

The received wave is detected by the vacuum tube oscillator O to yield currents of the signal frequencies in its plate-filament circuit. These currents are impressed through transformer T on the low pass filter FL and pass through this filter FL and amplifier A₁ to the indicator 12. The incoming and outgoing waves have carrier frequencies differing by an inaudible amount. The use of the amplifier is optional. Its usefulness in this circuit depends upon the degree of amplification otherwise obtained, as in the detector. The use of the filter FL is similarly optional. If the beat frequency wave resulting from the combination of the incoming and outgoing carrier waves is inaudible the elimination of this component is not required in order to avoid signal distortion. The use of the filter under these conditions would, however, result in more efficient indication of the signal, since the heating and overloading effects of those beat frequency currents are thereby avoided. If the beat frequency is audible but above the essential signal frequencies the filter is necessary in order to separate the beat frequency and signal components. The system of Fig. 1 may, of course, similarly include either one or both of these elements.

Since, in the particular method of modulation illustrated, both incoming and outgoing signal currents must appear in the plate-filament circuit of the oscillator-detector tube the locally transmitted signals tend to cause interference in the local receiver. This is avoided in the system of Fig. 2 by causing the signal currents from the modulator M to flow in relatively opposite directions through coils L₁ and L₂ which together constitute the primary of transformer T. Artificial network N is designed, with relation to the coils L₁ and L₂, so that their effects are balanced in the transformer secondary. Accordingly signal transmission is not accompanied by substantial side-tone in the local receiver. Artificial network N may be a simple impedance circuit as diagrammatically shown, capable of balancing the circuit through coil L₁ for low frequency currents, or it may be an oscillator generating a current of the frequency and wave form of the current from oscillator O, in which case the arrangement will insure a balance also for the small amounts of carrier frequency passing choke coil 17 and flowing in coil L₁. During reception the path of the low frequency detected currents which flow through coil L₁ is completed through the parallel paths which include, respectively, the

modulator tube M and the network N. The portion of this current which flows through coil L_2 is in such a direction as to aid the effect of that flowing through the coil L_1 .

5 Although the invention has been illustrated and described as embodied in a telephone system, it is not limited in application to such systems but may be applied to other types of signal systems. The essential features of the 10 invention may be embodied in widely different physical structures.

The scope of the invention is defined in the appended claims.

What is claimed is:

15 1. In a two-way high frequency signaling system, a device used in common for transmitting a high frequency wave and for detecting the modulating component of a received high frequency wave, said transmitted 20 and received high frequency waves differing in frequency by an amount above the highest essential frequency of the signal, a transfer circuit for the detected modulating component, and means in said transfer circuit for 25 preventing the flow therein of beat frequency current resulting from the intermodulation of the incoming and outgoing carrier waves.

2. In a two-way modulated wave signaling system, a repeating device for transmitting a 30 high frequency wave modulated in accordance with signals and for translating modulations of a high frequency received wave into signaling currents, a transmitter and a receiver for 35 signaling frequency currents associated with said repeating device, the frequencies of the two high frequency waves differing by an amount above the highest essential signal frequency, and a means in energy transfer relationship with said receiver which is adapted 40 to suppress currents of frequencies outside the range of signaling frequencies.

3. In a two-way system, a discharge device, a transmitting means for impressing high frequency waves upon said device for transmission, means for impressing received high frequency waves upon said device for detection, and a receiver and selective means associated 45 with said device for receiving exclusively the detected signal components of the received 50 wave, the frequencies of the respective high frequency waves differing by an amount at least higher than the highest essential signal frequency.

4. In a two-way signaling system, a circuit 55 for supplying high frequency modulated waves for transmission including a discharge device, said discharge device being designed to transmit high frequency waves and to detect received high frequency waves, and a 60 telephone receiver and a filter associated with the output circuit of said discharge device for receiving a detected component of the received high frequency waves to the exclusion of other frequencies, the frequencies of the 65 transmitted and received high frequency

waves differing by an amount above the highest essential signal frequency.

5. In a two-way signaling system, a three-electrode electric discharge device for both transmitting and receiving signals, a circuit connected between one electrode and a second electrode of said device for controlling the device as a three-electrode device in transmitting, a circuit connected between said first mentioned electrode and a third electrode of said device for controlling said device exclusive of said second electrode as a two-electrode device in receiving, the frequencies of the currents for transmission and reception differing in frequency by an amount above 70 the highest essential frequency of the signal, and a receiving circuit connected to said receiving electrodes, comprising a band-pass filter having an upper cut-off frequency between the highest signaling frequency and 75 said difference frequency.

6. The method of two-way high frequency signaling by means of a three-electrode electric discharge device having a cathode, an anode and an impedance controlling element 80 which consists in utilizing such device as a three-electrode discharge repeater for transmitting a signal modulated carrier wave and independently as a two-electrode electric discharge detector for receiving a signal modulated carrier wave whose frequency differs by an amount outside the range of essential signal frequencies from that of the transmitted carrier wave, and in selecting the detected components corresponding to the signal currents to the exclusion of the component corresponding to said difference frequency.

7. The method of operating a three-electrode discharge device having a cathode, an anode and an impedance control element in two-way signaling which comprises impressing outgoing signal waves between said cathode and impedance controlling element and transmitting the resulting waves derived between the anode and cathode to a remote station, receiving from said remote station incoming signal waves differing in frequency from the outgoing waves by a frequency greater than the essential frequency 105 range of speech currents, impressing said incoming signal waves between the cathode and anode of said device and deriving therefrom message indications whereby interaction of incoming and outgoing signals which might 110 result in noise currents which would interfere with the proper signal indications is 115 prevented.

8. In a two-way signaling system, means 120 for receiving signal waves incoming from a remote station, means for transmitting to said remote station signal waves differing from said incoming waves by a frequency exceeding the highest essential frequency of speech, and an electron discharge device hav- 125 130

ing a cathode, an anode and an impedance control element, said cathode and control element having a connection to said wave transmitting means, said cathode and anode having a connection to said signal wave receiving means whereby said electron discharge device may transmit the outgoing signal waves and may detect such received signal waves without producing any intermodulation component within the voice frequency range.

9. In a two-way system for transmitting low frequency signals, means for receiving from a remote station waves representing low frequency signals, means for transmitting to said remote station waves representing low frequency signals but differing in frequency from the received waves by an amount in excess of the highest essential frequency of said

low frequency signals, an electron discharge device having a cathode, an anode and an impedance control element, a circuit between said cathode and anode, means for impressing the received waves upon said circuit whereby they may be demodulated by said device operating as a two-element discharge device, a circuit connecting said cathode and impedance control element, means for impressing said outgoing waves upon said last-named circuit whereby the production by said device of intermodulation components falling within the essential frequency range of said low frequency signals is precluded.

In witness whereof, I hereunto subscribe my name this 5th day of January A. D., 1924.

JOHN F. FARRINGTON.
